UNITED STATES PATENT OFFICE

FREDERICK A. KROTZER AND WILLIAM B. CRANDALL, OF WESTFIELD, NEW YORK

LUMINOUS SIGN

Application filed January 19, 1929. Serial No. 333,675.

Our invention relates to improvements in signs of that type having a luminous display of characters indirectly exposed through reflection.

5 One of the objects of our invention is to provide a sign of this kind wherein replaceable elements or panels are employed, each bearing a figure or other character, applied thereto in reverse manner to be reflected through a mirror in luminous form; and to so mount or support the sign that it may be angularly adjusted with a view that the reflected figures of the sign will be clearly readable with the slightest ray of light and 15 from any given point of view.

Another object of our invention is the provision of a house-number sign embodying a support adapted to receive interchangeable figures, and means for luminously reflecting 20 the figures so that they may be seen at night under artificial light, even though such light be located at a distant point.

Another object of our invention is to provide a sign of the type mentioned having 25 new and novel means for receiving and supporting the character-bearing element or elements, and the mirror or other reflecting member through the medium of which the characters are luminously reflected.

30 With the above and other objects in view to appear hereinafter, our invention consists in the novel features of construction, and in the arrangement and combination of parts to be hereinafter described and more particularly pointed out in the subjoined claims.

In the drawings:

Fig. 1 is a perspective view of our improved luminous sign, particularly adapted for house number use.

40 Fig. 2 is a detached perspective view of one of the end members or plates of the sign.

Fig. 3 is a detached perspective view of the tie member used for tying the end members or plates together at one corner and for 45 supporting the character-bearing elements.

Fig. 4 is a vertical section, taken on line 4-4, Fig. 1.

Fig. 5 is an enlarged horizontal section, taken on line 5-5, Fig. 4.

50 Fig. 6 is a transverse section of the sign.

Fig. 7 is a detached perspective view of the intermediate portion of the sign which serves to support the reflecting member and the rear ends of the character-bearing elements.

Fig. 8 is a front elevation of a sign somewhat modified in construction and adapted more particularly for luminously displaying a name, or a word or words.

Fig. 9 is an end view of the construction illustrated in Fig. 8.

Fig. 10 is a cross section, taken on line 10-10, Fig. 8.

Fig. 11 is an enlarged vertical section, taken on line 11-11, Fig. 9.

Fig. 12 is an enlarged horizontal section, taken on line 12-12, Fig. 9.

In the drawings, the reference numeral 15 designates the frame or support of the sign by means of which the numeral or letter-bearing element or elements and the reflecting mirror are supported and retained in their relative positions with a view of reflecting the numerals or letters of one onto the other.

The frame or support comprises two end members or plates 16 which may have any desired outline, but are preferably ornamental and cast of malleable iron, aluminum, or other metal or alloy to provide the necessary rigidity, and to give the sign a finished appearance. We preferably form these plates so that they have a configuration somewhat approaching a triangle. Arranged in proximity to the upper end of each of these end members or plates is a groove 17, and near the lower edge, which is obliquely arranged, a second groove 18 is formed, both grooves 17 and 18 being on the inner side of the plate. The groove 18 converges toward the groove 17 at the rear end of the latter, as clearly shown in Fig. 2.

An intermediate member 19 is disposed between the two end plates and connects them together. This intermediate member is preferably formed of a sheet of metal bent to provide a comparatively wide mirror-supporting panel 20 and a wall member 21 disposed at an obtuse angle to said mirror supporting member. The front end of said sheet of metal is bent upon itself, as at 22,

to form a longitudinal groove 23, and near the upper end of the wall member 21 the sheet metal is bent upon itself to provide a supporting flange 24, which extends from 5 end to end of said wall member. The upper marginal portion of said wall member is bent forwardly along the major portion of its length to provide a retainer flange 25, which is spaced with reference to the supporting flange 24 to form a groove 26 between the two. Along the remaining marginal portion of said wall member, the metal is slit at intervals, as at 27, as best shown in Fig. 7, to provide a number of retainer lips or ears 15 28, which are adapted to be bent forwardly into alignment with the retainer flange 25 and which, when so bent, form a continuation of said retainer flange.

This intermediate member 19 is connected 20 at opposite ends to the end members or plates 16, and for this purpose the sheet metal from which said intermediate member is constructed is provided with three pairs of securing ears 29, 30, 31, respectively, the ears 25 29 being formed on and directed forwardly from the ends of the wall member 21 beneath and in slightly spaced relation to the supporting flange 24. The securing ears 30 are bent downwardly at opposite ends of the 30 mirror-supporting panel 20 at the junction of said panel with the wall member 21, and the ears 31 are bent downwardly at opposite ends of the mirror-supporting panel at or nears its front end.

35 The ears 29, 30 and 31 and the end edges of the intermediate member 19 lie in contact with the inner sides of the end walls or plates 16 and said intermediate member is fastened to said end members or plates by 40 means of screw bolts 32, 33, 34 passed through openings 35, 36, 37, respectively, in said end members or plates and through alined openings in said ears; nuts 38 being applied to the inner projecting ends of said 45 screw bolts, as best shown in Figs. 4 and 6. Before, however, connecting the intermediate member 19 to the end members or plates, a reflecting member or mirror 39 is placed upon the mirror-supporting panel 20 of said 50 intermediate member with its front marginal portion entered in the groove 23 extending along the front edge of said member, and it is secured to said mirror-supporting member at its rear edge by means of clips 55 40 stamped from the wall member 21 and bent downwardly onto the reflecting mirror, as best shown in Figs. 4 and 6.

Opposite ends of the reflecting mirror are 60 entered into the oblique grooves 18 in the end members or plates 16, packing 41 being preferably placed over the end marginal portions of this reflecting mirror and entered in said oblique grooves with the end portions of the mirror. This packing may be felt or other cushioning material and serves to firmly re-

tain the mirror in clamped condition between the end members or plates 16, without possibility of movement. This packing also guards against the elements of the weather entering behind the reflecting mirror and 70 damaging the prepared under side thereof; thus assuring retention of the reflecting qualities of the mirror.

A combined tie and supporting member 42 connects the end members at their upper 75 front ends; this member being preferably a casting provided with a groove 43 opening rearwardly, the groove 43 being in horizontal alinement with the groove 26 in the wall member 21 and with the grooves 17 in the end members or plates 16. This combined tie and supporting member has depending ears 44 at opposite ends, which lie against the inner sides of the end members or plates 16, and are provided with screw-threaded openings 45 which are alined with openings 46 in said end members or plates at their upper front corners. Fastening screws 47 are passed through the openings 46 in said end members or plates and threaded into the screw-threaded openings 45 in the depending lugs of the combined tie and supporting member 42.

In the construction shown in Figs. 1 to 7, which is particularly adapted to display house numbers, a plurality of number or numeral-bearing elements are provided. These elements are formed of glass of a preferred kind employed in signs of this type, and they are preferably oblong pieces or plates adapted to be supported in a horizontal plane and arranged edge to edge. Said numeral-bearing elements are designated by the numeral 48, and in the drawings, four of such elements are shown, although any other desired number may be employed. The rear ends of these elements are entered into the groove 26 on the wall member 21 of the intermediate member, being supported by the supporting flange 24 and retained in the groove by the retaining flange 25, including the ears 28 which form part of such retaining flange. The front ends of these numeral-bearing elements are entered in the retaining groove 43 formed in the combined tie and retaining member 42, and the outer side marginal portions of the end elements are entered into the horizontal grooves 17 formed in the end members or plates 16. The four number elements, when arranged end to end in firm contact, are co-extensive with the reflecting mirror underneath. Packing 49, similar to the packing 41, is placed over the outer side marginal portions of the two end numeral-bearing elements and fitted into the grooves 17 with said marginal portions.

When packing, such as indicated at 41 and 49 is employed, the grooves 17 and 18 in the end members or plates 16 are made somewhat wider than the thickness of the numeral-bear-

ing elements and the reflecting mirror, and the retainer grooves 23 and 26 in the intermediate member 19 and the groove 43 in the combined tie and retainer member 42 are of a size to snugly receive marginal portions of said numeral-bearing elements and reflecting mirror. If desired, however, packing similar to the packing 41 and 49 may be employed within the retainer grooves 23, 26 and 43, in which case each of said last-mentioned grooves will be made slightly wider than shown.

The numerals are outlined on the under side of the numeral-bearing elements, preferably by rendering such elements opaque outside of the numeral regions so that the region within the outline of each numeral or figure is left transparent, through which the rays of light may pass and the numerals be projected onto the reflecting mirror 39. These numerals appear reversed on the under side of the numeral-bearing elements so that when projected or transferred by light rays onto the mirror and reflected therefrom, they will appear luminously in correct display as though in upright position, all of which is well known in the art to which our invention relates.

A house number displayed by means of our sign may consist of one or more numerals, and where the house number consists of one or three numerals, we preferably employ three full-width elements, such as shown in the drawings, and two half-width elements, centrally positioning the full-width elements between the end members or plates 16 and placing the half-width elements at opposite ends of the three full-width elements, with the outer side marginal portions of the half-width elements entered into the grooves 17 in the end members or plates 16. In this manner a full-width element is centrally arranged in the frame or support of the sign. If a house number consists of one numeral, the numeral is outlined on the single center element so that it appears reflected through the reflecting mirror from a point centrally between its ends. If a house number consists of three numerals, the numerals are outlined on the three full-width elements under the arrangement described; and in such case, the house number is again centrally displayed on the reflecting mirror. Where house numbers consist of two or four numerals, four full-width elements are employed as shown, and in the case of two numerals being employed, they are displayed from the two intermediate elements, whereas, when four numerals are employed, they are displayed from all four elements. Consequently, in all cases, a house number will be centrally projected or transferred from the numeral-bearing elements or plates by light rays to the mirror and be luminously reflected from the mirror.

In order that the numeral-bearing elements may be conveniently inserted, the ears 28 formed at one end of the retainer flange 25 are kept in alignment with the major portion of the wall member 21 or, in other words, are left unbent, and as the combined length of these ears are somewhat greater than the width of each numeral-bearing element, three of the four elements may be inserted and properly positioned within their receiving grooves by entering the front ends of each in the receiving groove 43 formed in the combined tie and supporting element 42, thence lowering the plate to bring the rear marginal portion against the supporting flange 24, and finally sliding the elements one after the other lengthwise into the receiving grooves 26 and 43 until they are properly positioned. The end member or wall 16 adjacent the retainer lips 28 can then be loosened sufficiently to allow the last numeral-bearing element to be positioned in place, after which said end member or plate may be tightened to clamp all of the members together in a rigid manner. The retainer lips 28 are thence bent over the rear marginal portion of the element last inserted, and the innermost retainer lip 28 may slightly overlap a portion of the adjacent element in the series when bent downwardly, to form a continuation of the retainer flange 25.

By providing the retainer lips 28, it is possible to change the elements 48 without completely disassembling the parts of the sign; as it is only necessary to bend the retainer lips 28 upwardly, slightly loosen the adjacent end member or plate 16, after which any of the elements 48 may be withdrawn and others substituted, and when substituted, said end member or plate can be quickly tightened to completely fasten all parts together in a rigid manner. It will be apparent that an entrance opening for the retainer groove 26 is provided through the use of the retainer lips 28.

The frame or support, or casing, as it may be termed, consequently has vertical end walls formed by the end members or plates 16, a vertical rear wall formed by the wall member 21, a top wall formed by the elements 48, which may also be termed sign elements, and an inclined bottom wall having a reflecting upper surface. In this instance, a separate element in the form of a mirror is placed upon the true bottom wall formed of sheet metal 120 and being in piece with the vertical rear wall; the whole arranged to provide an opening at the front substantially co-extensive with the length and height of the casing. One or more of said sign elements have opaque and transparent regions, the transparent regions being outlined to the numerals or other characters to be displayed by painting the region around or without said numerals or characters, while the elements 125

not provided with numerals or other characters have their entire surfaces painted, or otherwise rendered opaque.

House numbers are invariably displayed at a comparatively high elevation, considered with respect to a person driving an automobile along the road in front of the house or walking along the sidewalk; and for this reason we provide means for adjustably supporting the sign, which consists of brackets 50 pivotally secured to opposite ends of the casing, the preferred form for a number sign being angular brackets, the securing arm 51 of which is parallel with the rear wall of the casing and adapted to be secured to a house, while the supporting arm 52, arranged at a right-angle to the securing arm, is provided with a bolt hole 53 at its front end through which a screw bolt 54 is passed, said screw bolt being entered in the end walls 16 of the casing and extending through the brackets, a thumb nut 55 being threaded onto each bolt to fasten the sign to said brackets, in any adjusted position, with a view of luminously reflecting the house number from the mirror 39 so that it appears centrally between the upper or rear edge and the lower or front edge of the mirror from a somewhat lower point of view.

It may here be stated that the sign element or elements used in luminous signs of this kind are usually colored, and it has been found that a blue color is easily readable and appears highly luminous when reflected through a mirror or other like reflecting medium. The reflections of the characters on the sign elements shown in Fig. 4 and of the sign element shown in Fig. 8, of the modified construction to be hereinafter described, are indicated as blue, but any other colored sign element or elements may be employed.

In the modification shown in Figs. 8 to 12, the intermediate portion of the sign, which comprises the sheet metal bottom wall 20 and the vertical rear wall 21, is depended upon to support the reflecting mirror only, since the supporting flange 26 shown on the wall member or rear wall 21 in the preferred construction is dispensed with; also the retainer clips 40 formed on said rear wall and the securing lugs 29, 30 and 31. In this modification, however, the front or lower end of the inclined bottom wall 20, which serves as the supporting panel for the mirror, is formed in the same manner as in the preferred construction to provide the receiving groove 23 to receive the front or lower marginal portion of the reflecting mirror 39, which mirror has its opposite ends inserted into the grooves formed in the inner sides of the end members or walls 16, as described. In this modification, a one-piece sign member or element 56 is employed, and like the numeral-bearing elements 48 in the preferred construction, forms the partly transparent and partly opaque top wall of the casing. This sign element 56 has

opposite ends entered into the grooves 17 in said end members or walls, while opposite ends of the reflecting mirror 39 are entered into the grooves 18 in said end members or walls 16, the packing 41 being provided within the grooves 18 for the ends of the mirror and the packing 49 within the grooves 17 for the ends of the sign element 56.

The upper marginal portion of the rear wall 21 has a finishing flange 57 bent forwardly therefrom so as to overlie the rear marginal portion of the sign element 56, and a finishing bar 58 of channel formation in cross section is fitted over the front marginal portion of the sign element 56. This finishing bar 58 may be otherwise shaped as it is not depended upon to support the sign plate and serves merely to protect the front edge of said plate against being chipped and to give the sign a finished appearance.

The intermediate member and the finishing bar 58 are simply clamped between the end members, no other provision being made for securing them in place, except the portions thereof overlying portions of the sign element and the reflecting mirror.

The end members or walls 16 are held in spaced relation and arranged to clamp the sign element and the reflecting mirror in a manner to prevent movement of both, by means of tie rods 59, 60, and 61, the tie rods 59 and 60 having opposite ends passed through the upper rear and upper front corners, respectively, of the end walls and having nuts 62 applied to their outer projecting ends so as to firmly press said end walls against the ends of the sign element 56 and reflecting mirror 39; against the ends of the intermediate member 19 forming the inclined bottom wall 20 and the rear wall 21; and against the finishing bar 58.

The ends of the tie rod 61 are passed through the end walls 16 at their lower front corners, and they project outwardly beyond said end walls a somewhat greater distance than the tie rods 59, 60. On the projecting ends of the tie rod 61, nuts 63 are applied which bear against the outer sides of said end walls and serve with the nuts 62 on the tie rods 59 and 60 to hold the various parts of the sign together in a rigid manner.

Supporting brackets 64 are provided at opposite ends of the sign, and these are pivotally connected to the projecting ends of the tie rods 61. Each of these brackets comprises a horizontal base or securing member 65 and a vertical or supporting member 66 which bears against the nuts 63 on the tie rod 61, and also against a boss 67 on the outer sides of the end walls 16. The supporting member 66 of each bracket is provided with a segmental slot 68 having the tie rod 61 as its center. The projecting ends of said tie rod are passed through the supporting members 130

66 of the brackets and have thumb nuts 69 threaded thereon.

Passed through the end walls 16 from their inner sides are clamping bolts 70 which extend axially through the bosses 67 formed on the outer sides of the end walls and project through the segmental slots 68 in the supporting members of the brackets, each bolt 70 having a thumb nut 71 threaded thereonto 10 which bears against its co-operating bracket.

The sign is therefore adjustably supported on the brackets; and in order to adjust the sign, it is only necessary to loosen the thumb nuts 71 and 69, after which the sign may be 15 swung to any desired angle on the projecting ends of the tie rod 61 and be held at such angle by tightening the thumb nuts 71 so that they bear firmly against the outer sides of the supporting members 66, after which the thumb 20 nuts 69 on the tie rod 61 may be tightened to further assure retention of the sign in its adjusted position. It is not absolutely necessary to maintain a tight pivotal mounting of the sign on the tie rod 61, since under ordinary circumstances the thumb nuts 71 will 25 hold the sign in any adjusted position.

While we have described the top wall of the frame or casing 15 in the preferred construction as numeral-bearing elements, and 30 in the modification as a sign element, we consider the term "sign plate" as applying to both forms, and to other elements whether flat, oblong, or otherwise, that could be substituted for the specific elements shown and 35 described.

Having thus described our invention, what we claim is:—

1. A luminous sign, comprising a casing having end walls, an intermediate member 40 forming an inclined bottom wall bent upon itself at its front edge to provide a retainer groove and having a vertically-disposed rear wall in piece with said bottom wall provided with a supporting flange and a retainer 45 flange separated from said supporting flange and having also retainer ears stamped therefrom directly above said inclined bottom wall, a reflecting mirror placed against said inclined bottom wall and having its 50 front marginal portion entered in said retainer groove and having its rear marginal portion engaged by said retainer ears, and a top wall having its rear marginal portion entered between said supporting flange and 55 said retainer flange and provided with means to throw characters outlined thereon downwardly onto said reflecting mirror to be reflected from the latter, and means engaging the front marginal portions of said top wall.

60 2. A luminous sign, comprising a casing having end members, an intermediate member connecting said end members in spaced relation and comprising an inclined bottom wall and a vertical rear wall, the front end of 65 said bottom wall having a retainer groove

extending lengthwise along the same and said rear wall having retainer ears adjacent its line of junction with said bottom wall, said rear wall having also a supporting flange above said retainer ears and a retainer flange 70 spaced from said supporting wall to provide a retainer groove therebetween, a combined tie and supporting member connecting said end walls in the plane of said supporting and retainer flanges, a sign plate extending 75 from end wall to end wall and having its rear marginal portion fitting into said retainer groove and its front marginal portion fitted into said combined tie and supporting member, and a reflecting mirror lying upon said inclined bottom wall and having its front marginal portion entered into the retainer groove at the front end of said bottom wall and its rear marginal portion engaged by the retainer ears on said rear wall. 80

3. A luminous sign, comprising a casing having end walls and an intermediate member formed of sheet metal bent upon itself to provide a forwardly-inclined bottom wall and a vertical rear wall, the metal of said rear wall being bent upon itself near its upper end to form a supporting flange and being further bent at its upper marginal portion in spaced relation to said supporting flange to provide a retainer flange, a portion 90 of said retainer flange being slit to form retainer ears capable of being bent upwardly into alignment with said rear wall and thus provide an entrance opening along a portion of said retainer flange, a supporting bar connecting said end walls at their upper forward corners, means for securing said intermediate member to said end walls, a reflecting mirror mounted on said inclined bottom wall, and a set of flat oblong elements supported by 95 said supporting flange and supporting bar and being capable of removal from and placement into said retaining groove through said entrance opening. 100

4. A luminous sign, comprising a casing 110 having a reflecting surface and two walls disposed at an angle to each other, one of said walls being formed of sheet metal bent upon itself to provide a supporting flange and having its marginal portion bent along the 115 major part thereof into a retainer flange in spaced relation to said supporting flange to provide a retainer groove, said last-mentioned wall being split along the remaining part of its marginal portion to provide re- 120 tainer ears adapted to be bent into alignment with said retainer flange and serve as a part thereof, means parallel with said retainer groove provided with a second retainer groove, and numeral-bearing elements hav- 125 ing opposite marginal portions fitted into said retainer grooves, said numeral-bearing elements being formed to cause numerals to be reflected from said reflecting surface.

5. A luminous sign, comprising a casing 130

- having end walls, a sheet metal intermediate member provided with ears at opposite ends through which and said end walls fastening means are adapted to be passed for connecting said end walls together by means of said intermediate member, said intermediate member having a retainer groove, a supporting element connecting said end walls in spaced relation to said retainer groove, a sign plate supported at its front marginal portion by said supporting element and at its rear marginal portion within said retainer groove, and a reflecting mirror disposed at an angle to said sign plate and receiving support from said intermediate member.
- 5 6. A luminous sign having a casing embodying means to luminously reflect characters outlined on a portion of said casing, and means to support opposite ends of said casing, said means comprising brackets to which the lower front end of said casing is pivotally connected, each of said brackets being provided with a segmental slot having the pivot of said casing as its center, bolts carried at opposite ends of said casing and passed through the segmental slots of said brackets, and thumb nuts applied to said bolts to bear against said brackets and hold said casing in any angular position.
- 10 20 25 30

In testimony whereof, we affix our signatures.
